UNITED STATES PATENT OFFICE.

JOHN M. THOMSON, OF DAVENPORT, IOWA.

FOLDING BED.

Application filed November 9, 1925. Serial No. 67,851.

This invention relates to an improved hinge for a folding bed of the type wherein the frame supporting the usual spring and mattress is pivotally connected at one end to a small truck frame so that the spring and mattress can be swung to a substantially vertical position to permit the bed, when not in use, to be stored in a comparatively small space, such as a closet.

10 An object of the invention is to provide such a hinge having a spring member operatively connected therewith to counterbalance the weight of the swinging bed when swung from a folded to an unfolded position.

15 A further and more specific object of the invention is to provide a folding bed hinge having a torsion spring mounted therein with means for adjusting the tension of the spring so that the counterbalancing force exerted 20 thereby will be sufficient to offset the weight of the swinging bed and its associated parts.

25 A further object is to provide a spring hinge having a single double-acting spring mounted therein, which spring functions to 30 counterbalance the weight of the swinging portion of the bed and provide a cushion therefor when swung to its normal inoperative position.

35 Other objects of the invention will appear 30 from the following description and accompanying drawings and will be pointed out in the annexed claims.

In the drawings there has been disclosed a 35 structure designed to carry out the various objects of the invention but it is to be understood that the invention is not confined to the exact features shown, as various changes may be made within the scope of the claims which follow.

40 In the accompanying drawings forming part of this specification,

Figure 1 is a view in side elevation of a folding bed showing the invention applied thereto;

45 Figure 2 is an enlarged detail sectional view on the line 2—2 of Figure 1 showing the general construction of the hinge;

50 Figure 3 is an end view of the upper portion of Figure 2 showing the hinge and the bed frame disconnected from the supporting frame;

55 Figure 4 is a view similar to Figure 3 taken on the line 4—4 of Figure 2;

Figure 5 is an end view of the torsion spring removed from the hinge; and

Figure 6 is a plan view of the supporting

truck frame with the bed frame removed therefrom.

In the selected embodiment of the invention here shown, there is illustrated a folding bed of ordinary construction, comprising a bed frame 6 having the usual flexible bottom 7 upon which the mattress 8 is mounted as shown. The legs 9 at the foot of the bed are preferably hinged as indicated by the dotted lines in Figure 1, so that when the frame 6, including the bottom 7 and mattress 8, is swung to its vertical day time position shown in dotted lines in Figure 1, the legs will assume the positions shown.

An important feature of this invention resides in the novel means provided for pivotally connecting the opposite end of the bed frame 6 to the supporting frame 11, which preferably is carried by suitable casters 12 as shown in Figure 1. The means provided for thus pivotally connecting the frame 6 to the uprights 14 of the supporting frame 11, preferably consists of blocks or sleeves 15 mounted upon and secured to each side rail of the frame 6 as shown in Figure 2. Each block 15 as a sleeve is provided with an outwardly extending boss 16 bored to receive one end of a pivot pin 17 suitably secured thereto. An annular flange or extension 18 is also formed on the sleeve 15 adapted to receive one end of a cylinder or spring housing 19 having a radial projection or tongue 21 depending therefrom adapted to be demountably received in a socket 22, terminally provided on the upright 90 post 14. The tongue 21 and also the opposed walls of the socket 22 are apertured to receive a cap screw or bolt 23 for the purpose of securing the tongue and the cylinder 19 to the post 14. It will be understood that both sides 95 of the stationary frame 11 are provided with the supporting standards 14 and these standards are equipped with the spring housings having bearings for the tilting frame.

A torsion spring 24 is concentrically mounted within the housing 19 and has one end seated upon the boss 16 as particularly shown in Figure 2. The ends of the spring 24 are preferably outwardly bent as shown in Figure 5 to provide the end-portions 25 and 26 which function to prevent the spring from 105 relatively rotating in the cylinder. The end-portion 25 is received in a slot 27 provided in the annular flange 18 of the block 15, and the opposite end-portion 26 is similarly seated in a slot 28 provided in the inwardly projecting annular flange 29 of a cap 31 adjust-

ably secured to the end of the housing 19 by means of cap screws 32. The end of the housing and also the abutting face of the cap 31 are provided with a series of small 5 ridges or notches 33 which cooperate with the screws 32 to prevent the cap 31 from relatively rotating upon the housing when the spring 24 is put under tension, as when the bed is lowered to its open position. Arcuate- 10 ly formed slots 34 are provided in the cap 31 to receive the screws 32 so that it may be relatively rotated upon the housing when it is desired to adjust the tension of the spring 24. Such adjustment is accomplished by 15 simply loosening the screws 32 and relatively rotating the cap upon the housing until the spring has been adjusted to the desired degree, after which the screws are tightened and the cap will be prevented from rotation 20 thereon as a result of the interlocking engagement with one another of the notches 33 provided upon the end of the housing and upon the adjacent face of the cap. Sockets 35 are provided in the outwardly extending hub 25 36 of the cap adapted to receive a suitable wrench or instrument for relatively rotating the cap when adjusting the tension of the latter as above described. A relatively smaller hub or boss 37 is provided on the 30 inner face of the cap 31 to provide a seat for the adjacent end of the spring 24 so that it will be concentrically retained within the housing.

Thus it will be seen that one end of the 35 spring 24 is connected to the pivot block 15 as a result of the end-portion 25 of the spring being seated in the slot 27 in the annular flange 18. The opposite end of the spring will be similarly connected or locked to the cap 31 and to the cylinder 19 by reason of the end-portion 26 of the spring being seated in the slot 28. Therefore, when the pivot block 15 is rotated with relation to the cylinder 19, in the operation of lowering the bed frame 6, the spring 24 will be put under tension as a result of one end being held stationary when the opposite end is being rotated with the block 15. Such increased tension in the spring 24 will be sufficient to 40 counterbalance the weight of the swinging frame 6 and associated parts. Should the tension in the spring 24 be insufficient to counterbalance the weight of the frame 6 when the latter is being lowered to its open 45 position, then the cap 31 may be relatively adjusted upon the cylinder 19 until the desired degree of tension in the spring is obtained, thereby providing means whereby the springs may be relatively adjusted to 50 counterbalance the weight of the bed frame, bedding, etc. The hub 36 of the cap 31 provides a bearing for one end of the pin 17 while the flange 18 at the opposite end of the pin will have a bearing in the cylinder 19, thereby providing a very substantial bearing 55 60 65

or pivotal connection between the frame 6 and the upright post 14.

Another feature of this invention resides in the particular construction, and tension adjustment of the spring 24 which will have a 70 dual function, that is, in addition to counter-balancing the weight of the frame 6, it also functions as a cushion or bumper to prevent the frame 6 from being jarred when folded from its open to the folded dotted line position shown in Figure 1. This cushioning effect is accomplished by offsetting the end-portion 26 as will be noted by reference to Figure 5, so that when the frame is in an upright position or at right angles to the 80 full line position in Figure 1, the end-portion 26 will be substantially in alignment with the end-portion 25 as indicated by the dotted line in Figure 5, thereby tending to slightly unwind the spring which, obviously, will put a 85 slight reverse tension thereon. The particular construction of this novel spring hinge is such as to render it well adapted for use in folding beds of the above character and its construction adapts it for manufacture at a 90 minimum cost. The usual head frame 38 of the bed is shown demountably mounted upon the truck frame 11 by means of the posts 39 secured to the frame 11. Instead of mounting the tilting bed frame on a truck frame it 95 may be supported by stationary brackets or hangers on the wall.

I claim as my invention:

1. A device of the class described, comprising a base having side rails, vertical standards secured to the side rails, each standard having a socket at its upper terminal, a cylinder for each standard having a projection removably engaged with the socket, the cylinders axially aligned crosswise of the base, 105 a bed frame having side rails each having a sleeve thereon, each sleeve having a lateral cylindrical extension rotatably engaged with the inner end of a cylinder, said extension having an axial bore and inwardly faced radial spring-end receiving slot, a cap rotatably engaged within each cylinder for angular adjustment, means for positively securing the cap in adjusted positions, said cap having an inwardly facing radial spring-end receiving slot, and a coiled torsion spring longitudinally disposed within each cylinder, said spring having radially disposed terminals engaging the slots as stops, said springs arranged to be slightly unwound or counter-tensioned immediately before the bed frame reaches its storage or upright position, to obtain a cushion effect. 115 120

2. A base, sockets axially aligned crosswise of the base at opposite sides thereof, a frame having side rails each of which has a projection rotatable upon one end of a corresponding socket, a cap rotatably adjustable upon the opposite end of each socket, and a coil spring within each socket having its ter- 125 130

minals respectively engaged with projection and cap, to submit the spring to torsion when the frame is lowered.

3. A base, sockets axially aligned crosswise of the base at opposite sides thereof, a frame having side rails each of which has a projection rotatable within one end of a corresponding socket, a cap rotatably adjustable within the opposite end of each socket, and a coil spring within each socket having its terminals respectively engaged with projection and cap, to submit the spring to torsion when the frame is lowered.

4. A base, sockets axially aligned crosswise of the base at opposite sides thereof, a frame having side rails each of which has a projection rotatable upon and closing one end of a corresponding socket, a cap rotatably adjustable upon and closing the opposite end of each socket, and a coil spring within each socket having its terminals respectively engaged with projection and cap, to submit the spring to torsion when the frame is lowered.

5. A base, sockets axially aligned crosswise of the base at opposite sides thereof, a frame having side rails each of which has a projection rotatable upon one end of a corresponding socket, a cap rotatably adjustable upon the opposite end of each socket, and a coil spring within each socket having its terminals respectively engaged with projection and cap, to submit the spring to torsion when the frame is lowered, means for securing the caps in adjusted position.

35 6. A base, sockets axially aligned crosswise of the base at opposite sides thereof, a frame having side rails each of which has a projection rotatable upon one end of a corresponding socket, a cap rotatably adjustable upon the opposite end of each socket, and a coil spring within each socket having its terminals respectively engaged with projection and cap, to submit the spring to torsion when the frame is lowered, said spring being arranged

45 to unwind or counter-tension immediately be-

fore the frame reaches its storage or upright position.

7. A base, sockets axially aligned crosswise of the base at opposite sides thereof, a frame having side rails each of which has a projection rotatable within one end of a corresponding socket, a cap rotatably adjustable within the opposite end of each socket, and a coil spring within each socket having its terminals respectively engaged with projection and cap, to submit the spring to torsion when the frame is lowered, means for securing the caps in adjusted position, and said springs being arranged to unwind or counter-tension immediately before the frame reaches its storage or upright position.

8. A base, sockets axially aligned crosswise of the base at opposite sides thereof, a frame having side rails each of which has a projection rotatable within one end of a corresponding socket, a cap rotatably adjustable within the opposite end of each socket, and a coil spring within each socket having its terminals respectively engaged with projection and cap, to submit the spring to torsion when the frame is lowered, each socket being detachably secured to its rail for removal in an upward direction.

9. A base, sockets axially aligned crosswise of the base at opposite sides thereof, a frame having side rails each of which has a projection rotatable upon one end of a corresponding socket, a cap rotatably adjustable upon the opposite end of each socket, and a coil spring within each socket having its terminals respectively engaged with projection and cap, to submit the spring to torsion when the frame is lowered, and a rod within each socket secured to the cap, traversing the spring and removably stepped in the projection.

In witness whereof, I have hereunto set my hand this 2nd day of November, 1925.

JOHN M. THOMSON.
